CLAIM

The ornamental design for a housing for amusement water toy, substantially as shown and described.

DESCRIPTION

FIG. 1 is a front perspective view of a housing for amusement water toy showing my new design;

FIG. 2 is a front elevational view thereof;

FIG. 3 is a top plan view thereof;

FIG. 4 is a left side elevational view thereof, the side opposite being substantially a mirror image;

FIG. 5 is a rear elevational view thereof; and,

FIG. 6 is a bottom plan view thereof.

FIG.1
